ELECTRIC SWITCH

Bascum O. Austin, Forest Hills, Pa., assignor to
 Westinghouse Electric & Manufacturing Company,
 East Pittsburgh, Pa., a corporation of
 Pennsylvania

Application April 14, 1934, Serial No. 720,611

7 Claims. (Cl. 200—98)

My invention relates, generally, to electric switches, and more particularly to switches of the electro-magnetic type wherein the contact members are actuated by electro-magnets.

5 An object of my invention, generally stated, is to provide an electric switch which shall be simple and efficient in operation and which may be economically manufactured and installed.

10 A more specific object of my invention is to increase the speed of operation of an automatic electric switch under overload or short-circuit conditions.

15 Another object of my invention is to provide a quick acting overload-trip mechanism for an electric switch.

Other objects of my invention will be either explained fully hereinafter or will be apparent to those skilled in the art.

20 In accordance with one embodiment of my invention, the moving contact arm of a switch is operated by the over-load trip mechanism without moving the main armature of the switch, thereby quickly opening the contact members by actuating the parts of the switch having a minimum weight.

25 For a fuller understanding of the nature and objects of my invention, reference may be had to the following detailed description taken in conjunction with the accompanying drawing, in which:

30 Figure 1 is a view, in side elevation of an electro-magnetic switch embodying my invention;

Fig. 2 is a view, in side elevation, of the switch illustrated in Fig. 1 showing the position to which the movable contact member of the switch is actuated by the overload-trip mechanism, and

35 Fig. 3 is a diagrammatic view illustrating the manner in which the switch may be connected in an electric circuit.

40 Referring now to the drawing, and particularly to Figs. 1 and 2, the switch which is illustrated comprises a main operating magnet 10 and an overload-trip magnet 11, both of which are mounted on an insulating base 12. The magnet 10 is provided with an energizing coil 13, a core 14 and an armature member 15 that is pivotally mounted on the frame 16 of the switch by a pin 17.

45 As shown, the overload-trip magnet 11 comprises a series or operating coil 18 and a holding coil 19, both disposed on one leg of a U-shaped member 21. The magnet 11 is provided with an armature member 22, also pivotally mounted at 17, which is actuated to the trip position shown in Fig. 2 when a predetermined value of current flows through the series coil 18. The holding

coil 19 will retain the armature 22 in the position shown in Fig. 2 after it has been raised to that position by the series coil 18.

5 The main armature 15 carries a movable contact member 23 that is disposed to engage a fixed contact member 24 when the armature is actuated to the position shown in Fig. 1 by the operating magnet 10. The contact member 23 is mounted on a contact-carrying arm 25 which is pivotally mounted on the armature 15 by a pin 26. A spring 27 is provided for resiliently pressing the movable contact member 23 against the fixed contact member 24.

15 In order that the contact members of the switch shall be opened quickly when the current in the overload coil 18 exceeds a predetermined value, the contact-carrying arm 25 is so connected to the downwardly extending arm 31 of the armature 22 by a link 32 that the contact-carrying arm 25 is actuated about its pivot point 26 to open the 20 contact members when the armature 22 is raised to the position shown in Fig. 2. After the contact members have been partially opened by the 25 overload-trip mechanism in the foregoing manner, the main operating magnet 10 is deenergized and the main armature 15 is permitted to drop to its lowermost position, thereby further opening the contact members of the switch.

30 In this manner the contact member 23 is disengaged from the contact member 24 without moving the main armature 15, thereby providing a means for interrupting the circuit through the contact members by operating the parts of the switch having a minimum weight, which makes it possible to greatly reduce the time required to open the contact members and interrupt the circuit. The opening speed of the switch under overload or short-circuit conditions is fast enough to limit the peak current, thus reducing the damage to other equipment that may be 40 connected in the circuit controlled by the switch.

35 As shown in Fig. 3, the switch herein described may be utilized as a line switch to connect a propelling motor 40 of an electric vehicle to a trolley conductor 41, the series coil 18 of the overload-trip magnet 11 being connected in the motor circuit when the contact members 23 and 24 of the switch are closed. The energizing coil 13 of the operating magnet 10 is energized through a contact segment 42, which may be on the master controller and an interlock member 43 which is actuated by the overload-trip mechanism.

45 As described hereinbefore, the series coil 18 will operate the overload-trip mechanism to partially 50

open the contact members of the switch when the current flowing through the coil exceeds a predetermined value. When the overload-trip mechanism is operated by the series coil 18, the 5 interlock 43 is actuated to interrupt the circuit through the main magnet coil 13 and to establish a circuit through the holding coil 19, thereby energizing the holding coil to retain the armature 22 in its uppermost position until the controller segment 42 is actuated to reset the overload-trip mechanism, after which the operating magnet coil 13 may be energized to reclose the contact members of the switch.

From the foregoing description, it is apparent 15 that I have provided a simple and quick acting overload-trip mechanism which may be readily applied to any switch of a type having a pivoted contact-carrying arm, such as the electro-magnetic switch shown in the drawing or a pneumatically-operated switch of a type well known in the art.

Since numerous changes may be made in the above-described construction and different embodiments of the invention may be made without departing from the spirit and scope thereof, it is intended that all matter contained in the above description or shown in the accompanying drawing shall be interpreted as illustrative and not in a limiting sense.

30 I claim as my invention:

1. In an electric switch, in combination, a fixed contact member, a movable contact member disposed to engage the fixed contact member, a pivotally-mounted contact arm for supporting the 35 movable contact member, means for actuating the movable contact member into engagement with the fixed contact member, and means for opening said contact members to an intermediate position between their fully open and fully closed 40 positions independently of the last named means.

2. In an electric switch, in combination, a fixed contact member, a movable contact member disposed to engage the fixed contact member, a pivotally-mounted contact arm for supporting the 45 movable contact member, means for actuating the movable contact member into engagement with the fixed contact member, and means for actuating the contact arm about its pivot point to open said contact members to an intermediate 50 position between their fully open and fully closed positions independently of the last named means.

3. In an electric switch, in combination a fixed contact member, a movable contact member disposed to engage the fixed contact member, a pivotally-mounted contact arm for supporting the movable contact member, means for actuating the movable contact member into engagement with the fixed contact member, and means responsive to a predetermined value of current 55 for actuating the contact arm about its pivot

point to open said contact members to an intermediate position between their fully open and fully closed positions independently of the last named means.

4. In an electric switch, in combination, a fixed 5 contact member, a movable contact member disposed to engage the fixed contact member, a pivotally-mounted contact arm for supporting the movable contact member, operating means for actuating the movable contact member into 10 engagement with the fixed contact member, and electro-magnetic means responsive to a predetermined value of current for actuating the contact arm about its pivot point to open said contact members to an intermediate position between their fully open and fully closed positions 15 independently of the operating means.

5. In an electric switch, in combination, a fixed contact member, a movable contact member disposed to engage the fixed contact member, 20 a pivotally-mounted contact arm for supporting the movable contact member, electro-magnetic operating means for actuating the movable contact member into engagement with the fixed contact member, and an overload device 25 responsive to a predetermined value of current for actuating the contact arm about its pivot point to open said contact members to an intermediate position between their fully open and fully closed 30 positions independently of the electro-magnetic operating means.

6. In an electric switch, in combination, a fixed contact member, a movable contact member disposed to engage the fixed contact member, a pivotally-mounted contact arm for supporting 35 the movable contact member, electro-magnetic operating means for actuating the movable contact member into engagement with the fixed contact member, and an electro-magnetic overload device having an armature member for actuating the contact arm about its pivot point to open said contact members to an intermediate 40 position between their fully open and fully closed positions independently of the electro-magnetic operating means.

7. The combination with an electric switch having a pivotally-mounted contact arm for supporting a movable contact member and operating means for actuating the movable contact member into engagement with a fixed contact member, of an electro-magnet having a pivotally-mounted armature disposed to actuate said contact arm about its pivot point to open said contact members to an intermediate position between their fully open and fully closed positions 50 independently of said operating means when the electro-magnet is energized by a predetermined 55 value of current.

BASCUM O. AUSTIN.
